UNITED STATES PATENT OFFICE

153,057

DESIGN FOR AN ELECTRIC HAIR CLIPPER

Ellis M. Brown, Racine, Wis., assignor to John Oster Manufacturing Company, Racine, Wis., a corporation of Wisconsin

Application January 21, 1948, Serial No. 143,954

Term of patent 14 years

(Cl. D22—3)

To all whom it may concern:

Be it known that I, Ellis M. Brown, a citizen of the United States, residing at Racine, in the county of Racine and State of Wisconsin, have invented a new, original, and ornamental Design for an Electric Hair Clipper, of which the following is a specification, reference being had to the accompanying drawings, forming part thereof.

Figure 1 is a perspective view of an electric hair clipper, showing my new design;

Figure 2 is a top view thereof;

Figure 3 is a side view thereof;

Figure 4 is a bottom view of the clipper;

Figure 5 is an end view;

Figure 6 is a cross sectional view taken on the plane of line 6—6 in Figure 4; and

Figure 7 is a cross sectional view taken on the plane of the line 7—7 in Figure 4.

The dominant features of my design reside in those portions thereof shown in full lines.

I claim:

The ornamental design for an electric hair clipper, as shown and described.

ELLIS M. BROWN.
